United States Patent Office

Des. 219,927
Patented Feb. 16, 1971

219,927

DRESSER

John H. Jordan, Jr., 8124 S. Crandon Ave.,
Chicago, Ill. 60617

Filed Aug. 29, 1969, Ser. No. 18,915

Term of patent 14 years

Int. Cl. D6—01

U.S. Cl. D33—6

FIG. 1.

FIG. 5.

FIG. 2.

FIG. 3.

FIG. 4.

FIG. 1 is a front perspective view of a dresser showing my design;

FIG. 2 is a top plan view of FIG. 1;

FIG. 3 is a left end elevation of FIG. 1;

FIG. 4 is a right end elevation of FIG. 1; and

FIG. 5 is an enlarged fragmentary view showing the left end of the lower front rail of FIG. 1 in greater detail.

The back of the dresser is conventionally plain and unornamented.

I claim:

The ornamental design for a dresser, as shown and described.
